UNITED STATES PATENT OFFICE.

ERASTUS E. WINKLEY, OF LYNN, MASSACHUSETTS.

SOLE-LEVELING MACHINE.

1,146,295.

Specification of Letters Patent. Patented July 13, 1915.

Application filed November 14, 1911. Serial No. 660,182.

To all whom it may concern:

Be it known that I, ERASTUS E. WINKLEY, a citizen of the United States, residing at Lynn, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The present invention relates to sole leveling machines, and more particularly to machines of this type which comprise a leveling roll and a shoe supporting jack movable to change the relative longitudinal position of the roll and jack.

The object of the present invention is to impart a more uniform and a greater transverse curvature to the shank of the shoe than can be obtained with existing machines of this type and to secure this result without detracting from the efficiency of the leveling operation upon the remaining portions of the shoe.

With this object in view, one feature of the invention consists in the provision of a shoe supporting jack, a leveling roll coöperating therewith, and means for retaining the opposite margins of the sole pressed down during the leveling operation.

A further feature of the invention consists in the combination with a leveling roll and shoe supporting jack, of means secured to the jack and arranged to impart an increased pressure to the shank of the shoe as the leveling roll passes thereover.

Still further features of the invention consist in certain novel features of construction, combinations and arrangements of parts hereinafter described and claimed, the advantages of which will be apparent to those skilled in the art from the following description.

In the accompanying drawings illustrating the preferred form of the invention, Figure 1 represents a side elevation partly in section of a shoe supporting jack with the improved device attached thereto and a leveling roll coöperating therewith; and Fig. 2 is a section upon the line 2—2 of Fig. 1 looking in the direction of the arrows.

The illustrated embodiment of the invention is shown in connection with a leveling machine of the type shown and described in

the patent to Winkley, 555,548, dated March 3, 1896. In this type of machine, mechanism is provided for changing the relative longitudinal position and lateral inclination of the leveling roll and jack in order to properly level the sole of the shoe, as is well known to those skilled in the art, and which forms no part of the present invention.

Considerable difficulty has been experienced in designing a leveling machine which will accommodate a variety of classes of work and with which the requisite transverse curvature at the shank of the shoe can be secured. In the present type of machine, when the roll is inclined laterally to press down one margin of the shank, it tends to raise the opposite margin of the shank and if that margin has been previously pressed down by the leveling roll the rounded effect thus secured is partially or wholly lost. In the present invention, this tendency is avoided by providing a pad which presses upon opposite margins of the sole simultaneously to force them down and retain them in this position during the entire leveling operation. The pressing pad is operatively connected to the jack and is secured in position upon the sole after the shoe is jacked and prior to the leveling operation. As the pad exerts a direct pressure upon opposite margins of the sole, it may be considered as an independent device for leveling the shank, which may be used in conjunction with the leveling roll or not, as desired. As the leveling roll is traversed back and forth over one margin of the shank, an increased pressure is exerted upon that portion of the sole in addition to the pressure which is constantly maintained upon the opposite margins of the sole by the pressing pad.

The shoe supporting jack is indicated at 1 and is provided with the usual toe post 2 and the last pin 3 to enable the shoe to be properly supported thereon. The jack is secured upon a rock shaft 4, about which it is oscillated to move the shoe longitudinally of a leveling roll indicated at 5. The pressing pad is indicated at 10 and is formed of a strip of leather of suitable width passed over the shank of the shoe and connected at its opposite ends to the shoe supporting jack 1. From an inspection of Fig. 1, it will be noted that the pressing pad 10 is of

sufficient thickness to raise the leveling roll above the plane of the sole when it passes thereover, thus securing an increased pressure upon this portion of the sole as the 5 downward movement of the leveling roll is imparted by a spring connection secured to a fixed portion of the machine frame. The plane of the sole refers to a plane lying substantially in the ball portion of the sole and 10 below which the shank portion of the sole lies so that normally the leveling roll exerts a less pressure upon the shank than at the ball of the sole. The pressing pad 10 is reinforced longitudinally with a metal plate 11 and transversely with a similar metal plate 12 which enables the pad to retain approximately its true form without being broken by the action of the leveling roll or by the downward pull upon its opposite 15 ends. The opposite ends of the pad 10 are yieldingly connected to a pair of arms 15 which are pivoted at 16 to the jack and as the connections between each arm and the corresponding end of the pad are identical 20 only a single set of connections will be hereinafter described. A clip 17 is rigidly secured to the end of the strap and is provided with a depending ear to which a link 18 is pivotally connected. The link 18 is 25 operatively connected to the arm 15 through a slide 19 and a rod 20 which is pivotally connected to the slide at 21 and to arm 15 at 30 22. In order to provide a yielding connection between the arm 15 and the strap a spring 23 is interposed between the upper end of the slide 19 and a collar 24 secured to the rod 18. Owing to the provision of 35 the pivotal connections between the various elements, the ends of the strap are pulled down and are free to move both longitudinally and laterally upon depressing the arms 40 15. The arms 15 project rearwardly from a handle 25 which is conveniently accessible to the operator in order that they may be 45 manipulated readily to seat the pad 10 upon the shoe. The arms 15 are locked in a depressed position with the pad pressing firmly upon the shank of the shoe by a ratchet toothed segment 26 formed upon the 50 jack and engaged by a spring pressed latch pin 27 slidingly supported upon the handle 25.

After the shoe has been jacked, the pressing pad 10 is seated upon the shoe and the 55 handle 25 is depressed to put the springs 23 under compression and exert a yielding pressure upon opposite margins of the sole. The latch pin 27 then acts automatically to retain the pad in this position, pressing 60 down opposite margins of the sole. As the leveling roll is traversed back and forth longitudinally of the sole, it is inclined laterally to bear upon opposite margins of the sole successively and after the roll has 65 pressed one margin of the sole down, the pad

continues to engage with the sole and retains the margin in its depressed position. Thus as the leveling roll continues to move back and forth over the margin of the sole and presses the same down by small increments, the pad 10 prevents the sole from 70 springing back to its initial position after each passage of the leveling roll thereover, and when the leveling roll is inclined to operate upon the opposite margin of the sole, the pad prevents the raising of the margin which has been leveled. The under side of the pad is beveled off slightly where it projects over the ball line of the shoe so that 75 no mark or impression is formed in the sole at the line where the pad terminates and the roll rides on to the surface of the sole. 80

While it is preferred to employ the specific construction and arrangement of parts shown and described, it will be understood 85 that this construction and arrangement is not essential except so far as specified in the claims, and may be changed or modified without departing from the broader features of the invention. 90

Having thus described the invention, what is claimed is:

1. A sole leveling machine having, in combination, a shoe supporting jack, a leveling roll coöperating therewith and arranged to engage successively with opposite marginal portions of the shank, a pressure pad bearing upon opposite margins of the shank simultaneously, and means for pressing the pad into engagement with the sole, substantially as described. 95

2. A sole leveling machine having, in combination, a shoe supporting jack, a leveling roll coöperating therewith and arranged to engage with opposite margins of the sole 100 successively, a pressure pad extending across the shank and bearing upon opposite margins simultaneously, an actuating member, and yielding connections between each end of the pad and the actuating member, substantially as described. 110

3. A sole leveling machine having, in combination, a shoe supporting jack, a leveling roll coöperating therewith, and means secured to the jack and arranged to impart an increased pressure to the shank of the shoe 115 as the leveling roll passes thereover, substantially as described.

4. A sole leveling machine having, in combination, a jack arranged to support the 120 shoe, means for exerting a direct pressure upon the shank of the shoe, and a leveling roll arranged to supplement the action of the pressure exerting means, substantially as described. 125

5. A sole leveling machine having, in combination, a shoe supporting jack, means for exerting a yielding pressure upon opposite margins of the sole simultaneously, and means for increasing the pressure upon one 130

margin of the sole while maintaining the yielding pressure upon opposite margins of the sole, substantially as described.

6. A sole leveling machine having, in combination, a shoe supporting jack, a leveling roll coöperating therewith, a pressing pad seated upon the shank of the shoe, and means for yieldingly forcing the pad into engagement with the shoe, substantially as described.

7. A sole leveling machine having a shoe supporting jack comprising a toe post and a heel post, a leveling roll, a strap passing over the shank of the shoe and arranged to coöperate with the leveling roll to level the shoe, a lever pivoted to the jack at one end and connected to the shank strap between its ends, and means for locking the lever in a depressed position to maintain the strap in engagement with the shoe sole, substantially as described.

8. A sole leveling machine having, in combination, a shoe supporting jack, a pressing pad seated upon the shank of the shoe, a pair of arms pivoted to the jack, operative connections for yieldingly securing opposite ends of the pad to the arms, and means for locking the arms in a depressed position, substantially as described.

9. A sole leveling machine having a shoe supporting jack comprising a toe post and a heel post, a leveling roll, a strap passing over the shank of the shoe and arranged to coöperate with the leveling roll to level the sole, a lever pivoted at one end adjacent the front of the jack and connected to the shank strap, a toothed locking member, and a latch pin mounted upon the lever and engaging with the locking member to retain the lever in a depressed position.

10. A sole leveling machine having, in combination, a shoe supporting jack, a pres-

sure pad arranged to bear directly upon the shoe sole, means for pressing the pad into engagement with the sole, and a leveling roll coöperating with the pad to level the sole, substantially as described.

11. A sole leveling machine having, in combination, a shoe supporting jack, a pressure pad bearing upon the shank of the shoe sole to shape the sole to the desired curvature by direct pressure, and a leveling roll coöperating with the pad to apply a leveling pressure to the sole through the pad, substantially as described.

12. A sole leveling machine having, in combination, a shoe supporting jack, a pressure pad conforming substantially to the desired curvature of that portion of the shoe sole with which it engages, and a leveling roll coöperating with the pad to exert a leveling pressure upon the sole indirectly through the pad, substantially as described.

13. A sole leveling machine having, in combination, a shoe supporting jack, a flexible pad engaging with the shank portion of the shoe sole and conforming substantially to the desired curvature of the sole, and a leveling roll coöperating with the pad to level the sole, substantially as described.

14. A sole leveling machine having, in combination, a shoe supporting jack, a pressure pad bearing upon the shoe sole and arranged to shape that portion of the sole with which it engages into conformity with the last by a direct pressure, and a leveling roll arranged to exert an indirect pressure upon a portion of the sole engaged by the pad, substantially as described.
